UNITED STATES PATENT OFFICE.

BELVIN T. WILLISTON, OF SOMERVILLE, MASSACHUSETTS, ASSIGNOR TO THE UNITED INJECTOR COMPANY, OF NEW YORK, N. Y., A CORPORATION OF NEW YORK.

WATER-HEATER.

1,072,197.

Specification of Letters Patent.

Patented Sept. 2, 1913.

Application filed May 10, 1912. Serial No. 696,379.

To all whom it may concern:

Be it known that I, BELVIN T. WILLISTON, a citizen of the United States, and resident of Somerville, in the county of Middlesex 5 and State of Massachusetts, have invented new and useful Improvements in Water-Heaters, of which the following is a specification.

My invention relates to apparatus for 10 heating water, and particularly to that class of such apparatus wherein water is heated by means of a steam jet which heats the water by condensation.

The particular object of my invention is 15 to provide an automatic heater of this class which shall be adapted to use steam at low pressure and to regulate the quantity of steam admitted to the body of water, so that the temperature thereof shall not rise 20 above a predetermined degree. My invention is, moreover, designed to enable exhaust steam from locomotive cylinders to be used for maintaining a suitably high temperature of the feed water supply carried in the 25 tank, and for this reason sundry special features of my invention, herein to be described, are provided.

The advantage and utility of heating the feed water supply of a steam boiler have 30 long been known, and in locomotive practice feed water has been heated by means of the boiler feeding injectors by causing the injectors to blow back live steam through the tank connection; but while this has, of 35 course, sufficed to heat the water, there is no economy in the practice. On the other hand, by utilizing exhaust steam a saving is effected, which, measured in terms of the fuel consumed under the boiler, may under 40 some conditions rise as high as 7 per cent. The boiler feeding injectors, however, are subject to certain limitations in respect to the temperature of feed water which the injector can efficiently force into the boiler, and 45 therefore any feed water heating contrivance which is liable to overheat the feed water cannot be expected to meet with the approval of engineers.

My invention herein described provides a 50 feed water heater which may be used effectively with exhaust steam and which automatically reduces or ceases its operation when the feed water in the tank has reached a practical predetermined limit of tempera- 55 ture.

In the drawings hereto annexed there is illustrated an example of my invention as embodied in a feed water heater, which is shown in vertical, longitudinal section.

There are various means for imparting 60 the heat of steam to water in which said means may be immersed, such as steam coils, or steam tubes in which the steam itself does not mingle with the water to be heated, or ejectors by which the steam heats the 65 water by mingling directly with it. Any means for imparting the heat of steam to water in which the heating means is submerged will serve: for purposes of illustration I show the heating means as an ejector, 70 which I believe on the whole to be preferable.

Referring to the drawing, A generally represents the casing of the water heater, which is preferably made in the form of a 75 casting in as many parts as may be required by the design of the instrument and the necessities of the foundry. The partitions in this casing divide it into several chambers, of which 1 is the steam chamber, 80 2 the steam tube or jet, and 3 the combining or circulating tube. A reducing valve presently to be described forms a partition or boundary for another chamber marked 4, which will be referred to as the back pres- 85 sure chamber.

The heating and circulating portions of the apparatus comprise the essential members of the well-known ejector, namely, the steam tube S' and the combining tube B, 90 which in the instance shown is supplemented by a secondary water tube B². The combining tube B has an inlet opening at L and an outlet at O.

Steam is admitted to the instrument 95 through the steam inlet S to which a pipe may be coupled to provide a connection with the exhaust chambers associated with the steam cylinders of a locomotive engine. Steam which enters at this orifice S passes 100 into the steam chamber 1 and fills that chamber, the back pressure chamber 4 and the jet space 2, and passes through the steam tube S' to mingle with and heat the water in the tank. As the entire heating apparatus is 105 intended to be immersed in the tank near the bottom thereof, steam which emerges from the tube S' sets up a circulation of water which enters at L and emerges at O, so that all of the water in the tank sooner 110

or later passes through the heating apparatus.

In order to prevent water either of condensation or from the tank from passing into the exhaust steam connection through the orifice S, there is provided a check valve C, of which the stem C' slides in a suitable bearing in the bridge-bar B'. This valve when closed rests upon the valve seat C².

10 The admission of steam into the steam tube S² is controlled by the reducing valve V, which comprises the piston valve P and the disk valve V', the latter seating at V³ while the former is suitably packed to slide 15 in the cylindrical bearing at A'. The piston valve portion P is perforated at P' so as to afford free entrance of steam into the back pressure chamber 4. The casing of the instrument is perforated as at D' and the 20 aperture so made is under the control of a valve D, which in turn is operated by a thermostat. In the instance here shown, the thermostat consists of a Bourdon tube T fixed at T' and with its free end at T². A 25 rod T³ is fixed to the free end T² and enters a socket at T⁴ at the fixed end of the tube. On the free end of the tube T² the tube is 30 attached to valve D by means of a pin D³, this pin having some play so that the movement of the Bourdon tube T is communicated to the valve D through the spring D⁴. The thermostat and its connections are 35 inclosed in a housing G secured to the casing of the instrument by studs G'. This housing G is entirely open at the sides, so that the Bourdon tube T is immersed in the water of the tank. Adjustment of the thermostat is provided by the adjusting screw at T⁵.

The reducing valve V is centered and 40 steadied by means of stems V², V⁵, which slide respectively in the recess L' formed in the back plate L², and in the bridge-bar B².

The operation of the above described apparatus is as follows: Connection being 45 made to the exhaust steam of the engine through the aperture S and this steam connection being open, this steam finds its way into the heater by lifting the check valve C. Assuming that the water in the tank is 50 cold,—the regulating valve D will be drawn from its seat by the Bourdon tube T and consequently back pressure on the reducing valve V cannot develop and such steam pressure as is produced in the chamber 1 will 55 open the valve V' if it is not already open. Steam thus passes into the jet chamber 2 and out from the steam tube S' heating and circulating the water, and continues so to operate until the rise of temperature of the 60 water has so far expanded the Bourdon tube T that the valve D is seated and the aperture D is closed. Here the function of the spring D⁴ comes into play, since it relieves the Bourdon tube T of any strain which 65 might result from pressure by expansion.

The relief aperture D' being closed, the vapor pressure in the back pressure chamber 4 approaches that in the steam chamber 1, and by reason of the lower vapor pressure maintained at the entrance 70 of the tube chamber 2 the preponderance of pressure is then established at the back of the valve V which moves to bring the valve V' toward its seat V³, thus reducing the quantity of steam which may enter 75 the steam tube S for water heating purposes. This operation may result in completely closing the disk valve V upon its seat V³, or, it may be, under other conditions result in merely regulating the amount of opening 80 for steam, drawing it at the valve seat V³. The valve C will usually be raised but a short distance from its seat C² and serves as an effective check against entrance of 85 water to the steam connections.

The advantage of feed water heaters of this character will perhaps be best obtained by its use in connection with a non-lifting injector, which can efficiently take and feed water at higher temperatures than are desirable in the case of lifting injectors; but whatever may be the desired temperature of the feed water, it can be determined and maintained by adjusting the thermostat which controls the behavior of the reducing 90 valve which in turn regulates the quantity of steam to be used for heating water.

What I claim and desire to secure by Letters Patent, is:

1. The combination in a water heater, of 100 means adapted to impart the heat of steam to water in which such means is immersed, a reducing valve to control admission of steam to said means, comprising a relatively large piston valve and a relatively small disk valve, the latter seating over the steam-entrance to said means, a casing for 105 said reducing valve, said casing being apertured at the rear of the reducing valve, a back pressure valve controlling said aperture, and a thermostat in control of the back pressure valve.

2. The combination in a water heater, of 110 means adapted to impart the heat of steam to water in which such means is immersed, a reducing valve to control admission of steam to said means, comprising a relatively large piston valve and a relatively small disk valve, the latter seating over the steam-entrance to said means, a check valve between 115 the said heating means and the source of steam supply, a casing for said reducing valve, said casing being apertured at the rear of the reducing valve, a back pressure valve controlling said aperture, and a thermostat in control of the back pressure valve.

3. The combination in a water heater, of 120 means adapted to impart the heat of steam to water in which said means is immersed, a reducing valve, to control admission of 125

steam to said means, comprising a relatively large piston valve and a relatively small disk valve, said piston valve being provided with a small aperture, the disk valve seating over the steam entrance to said heating means, a casing for said reducing valve, apertured at the rear of said valve, a back pressure valve controlling said aperture in the casing, and a thermostat in control of the back pressure valve.

4. The combination in a water heater, of means adapted to impart the heat of steam to water in which such means is immersed, a reducing valve to control admission of steam to said means, comprising a relatively large piston valve and a relatively small disk valve, a check valve between said heating means and the source of steam supply, a casing for said reducing valve, said casing being apertured at the rear of the reducing valve, a back pressure valve controlling said aperture, and a thermostat to control the back pressure valve.

5. The combination in a water heater, of an ejector adapted to be immersed in liquid to be heated, said ejector comprising a casing which contains a steam chamber, a steam tube, a combining tube, a reducing valve in the steam chamber to control the steam tube entrance, comprising a relatively large piston valve and a relatively small disk valve, the latter seating over the steam tube, the casing being apertured at the rear of the reducing valve; a back pressure valve controlling said aperture, and a thermostat in control of the back pressure valve.

6. The combination in a water heater of an ejector adapted to be immersed in liquid to be heated, said ejector comprising a casing and within the casing a steam chamber, a steam tube and a combining tube; a reducing valve in the steam chamber to control the steam tube entrance, comprising a relatively large piston valve and a rela-

tively small disk valve to control the entrance to the steam chamber, the casing being apertured at the rear of the reducing valve, a back pressure valve controlling said aperture, and a thermostat in control of the back pressure valve.

7. The combination in a water heater of an ejector adapted to be immersed in liquid to be heated, said ejector comprising a casing and within the casing a steam chamber, a steam tube, and a combining tube; a reducing valve in the steam chamber to control the steam tube entrance, comprising a relatively large piston valve, and a relatively small disk valve, said piston being provided with an aperture, the disk valve seating over the steam tube, the casing being apertured at the rear of the reducing valve, a back pressure valve controlling said aperture and a thermostat in control of the back pressure valve.

8. The combination in a water heater of an ejector adapted to be immersed in liquid to be heated, said ejector comprising a casing and within the casing a steam chamber, a steam tube, and a combining tube; a reducing valve in the steam chamber to control the steam tube entrance, comprising a relatively large piston valve, and a relatively small disk valve, said piston valve being provided with an aperture, the disk valve seating over the steam tube, a check valve to control the entrance to the steam chamber, the casing being apertured at the rear of the reducing valve, a back pressure valve controlling said aperture, and a thermostat in control of the back pressure valve.

Signed by me at Boston, Massachusetts, this fourth day of May 1912.

BELVIN T. WILLISTON.
